FIG. 1 is a top plan view of a corrugated pipe showing my new design;

FIG. 2 is a side elevational view thereof;

FIG. 3 is a bottom plan view thereof;

FIG. 4 is an end view taken from the left of FIG. 1;

FIG. 5 is a sectional view thereof taken along line 5—5 of FIG. 2;

FIG. 6 is a sectional view thereof taken along line 6—6 of FIG. 3;

FIG. 7 is a bottom plan view of a second embodiment of the corrugated pipe shown in FIG. 1 with the top being the same as shown in FIG. 1;

FIG. 8 is a bottom plan view of a third embodiment of the corrugated pipe shown in FIG. 1 with the top being the same as shown in FIG. 1;

FIG. 9 is a bottom plan view of a fourth embodiment of the corrugated pipe shown in FIG. 1 with the top being the same as shown in FIG. 1;

FIG. 10 is a top plan view of a fifth embodiment of the corrugated pipe shown in FIG. 1;

FIG. 11 is a side elevational view of FIG. 10;

FIG. 12 is a bottom plan view of FIG. 10;

FIG. 13 is an end view taken from the left of FIG. 10;

FIG. 14 is a sectional view taken along line 14—14 of FIG. 11;

FIG. 15 is a sectional view taken along line 15—15 of FIG. 12;

FIG. 16 is a bottom plan view of a sixth embodiment of the corrugated pipe shown in FIG. 1 with the top being the same as shown in FIG. 10;

FIG. 17 is a bottom plan view of a seventh embodiment of the corrugated pipe shown in FIG. 1 with the top being the same as shown in FIG. 10;

FIG. 18 is a bottom plan view of an eighth embodiment of the corrugated pipe shown in FIG. 1 with the top being the same as shown in FIG. 10;

FIG. 19 is a top plan view of a ninth embodiment of the corrugated pipe shown in FIG. 1;

FIG. 20 is a side elevational view of FIG. 19;

FIG. 21 is a bottom plan view of FIG. 19;

FIG. 22 is an end view taken from the left of FIG. 19;

FIG. 23 is a sectional view taken along line 23—23 of FIG. 20;

FIG. 24 is a sectional view taken along line 24—24 of FIG. 21;

FIG. 25 is a bottom plan view of a tenth embodiment of the corrugated pipe shown in FIG. 1 with the top being the same as shown in FIG. 19;

FIG. 26 is a bottom plan view of an eleventh embodiment of the corrugated pipe shown in FIG. 1 with the top being the same as shown in FIG. 19; and

FIG. 27 is a bottom plan view of a twelfth embodiment of the corrugated pipe shown in FIG. 1 with the top being the same as shown in FIG. 19.

A portion of the corrugated pipe has been broken away in FIGS. 1, 2, 3, 7, 8, 9, 10, 11, 12, 16, 17, 18, 19, 20, 21, 25, 26 and 27 to indicate indeterminate length.

I claim:

The ornamental design for a corrugated pipe, substantially as shown and described.
